[57] CLAIM

The ornamental design for a reclining chair, substantially as shown and described.

DESCRIPTION

FIG. 1 is a perspective view of the reclining chair contemplated herein in the set-up position;

FIG. 2 is a perspective view of the chair shown in FIG. 1, but in the knock-down folded position;

FIG. 3 shows the chair of FIG. 1 in the open position from the front; the fragmentary depicted fabric of the seat and backrest members therein is continuous throughout as in FIG. 1;

FIG. 4 shows the chair of FIG. 1 in the open position from the rear; the fragmentary depicted fabric of the seat and backrest members therein is likewise continuous;

FIG. 5 shows the chair of FIG. 1 from the top; the fragmentary depicted fabric of the seat and backrest members therein is likewise continuous;

FIG. 6 shows the chair of FIG. 1 from the bottom; the fragmentary depicted fabric of the seat and backrest members therein is likewise continuous;

FIG. 7 is a left perspective view of the chair of FIG. 1 with the back straight;

FIG. 8 is a right perspective view of the chair of FIG. 1 with the back straight; and,

FIG. 9 presents a perspective view of the chair of FIG. 1 with the back expanded.
